UNITED STATES PATENT OFFICE.

ALONZO ALDRICH, OF BELOIT, WISCONSIN.

PAPER-MAKING MACHINE.

Application filed May 14, 1921. Serial No. 469,553.

My invention relates to paper making machines, particularly of the Fourdrinier variety. The invention relates more particularly to that part of the machine by 5 which the material is fed to the wire.

One of the objects of the invention is to provide a practical and effective material feeding mechanism.

Another object of the invention is to 10 simplify such mechanism, completely eliminating the complicated arrangements which are now in common use in machines of this character.

Another object of the invention is to 15 provide a simple and practical arrangement for adjusting the flow or feed of the material.

In the accompanying drawings Fig. 1 is 20 a side elevation of a part of a paper making machine embodying my present invention;

Fig. 2 is a similar elevation of a part of 25 the mechanism shown in Fig. 1, adjusted to a different position;

Fig. 3 is an end elevation of the same;

Fig. 4 is a view similar to Fig. 3 of a portion of a modified form of device; and

Fig. 5 is a view similar to Fig. 1 of a 30 still further modification.

Referring to the drawings, I show a box 1 which is understood to contain pulp or 35 suitable material for the making of paper, such material being shown at 2. The drawings also show part of a table 3 provided with rolls 4—4 mounted on journals 5—5 and on these rolls 4—4 is the wire 6 which travels around the breast roll 7 supported in bearings 8. Above the table 3 and wire 6 is a deckel strap 9 mounted on a deckel 40 wheel 10, the strap 9 resting upon the wire 6. The deckel wheel 10 is supported by a support 11 bolted to the table 3 by bolts 14.

An outlet preferably in the form of a 45 nozzle or spout 16 is attached to the head box 1, preferably so that its open end shall clear the wire 6 at the top of the breast roll, between the deckel strap 9 and another deckel strap which is understood to be on 50 the opposite side of the wire 6. From the head box 1 the material for the paper may flow through this spout 16 on to the wire 6. For controlling the flow from the box, I show a vertically adjustable gate or shutter 17 arranged to slide vertically on the in-

side of the tank wall and arranged to more or less open and close the aperture 18 which affords communication between the interior of the box 1 and the spout or nozzle 16. For adjustment of this gate 17 a rod 19 60 is shown, extending up to the top of the box and projecting above the same and having a handle 20 by which it may be adjusted so as to raise and lower the gate 17.

To permit the flow of material from the 65 spout 16 to be adjusted the outlet or orifice 21 of said spout is preferably made adjustable, as for example by hinging the upper wall 22 thereof as at 23 so that said upper wall may be swung up and down. As a 70 means of making adjustment, I show an adjusting screw 24 which is arranged in a bearing 25 and has at its end a loose connection with a cleat 26 on the swinging cover 22. By turning the screw 24 the 75 member 22 may be swung up and down and the size of the orifice 21 varied. In Fig. 1 the member 22 is shown in a rather elevated position, whereas in Fig. 2 80 said member is shown in a lowered position with the orifice more contracted. As shown in Fig. 3, it is preferable to have a plurality of screws 24 located at intervals along the length of the member 22, so that 85 adjustment may be made of the entire length of said member. The discharge end of the upper plate or member 22 may be sprung up or down by screws 24 to make flow opening more or less at center than 90 towards the sides.

In Fig. 4 is shown a modification in which the member 22 is made in sections 22'—22', and each section provided with a separate screw 24'—24', so that the orifice 21 may be adjusted to different sizes at different 95 points in its length if desired.

In Fig. 5 is shown a still further modification, in which the support for the deckel wheel 10 is somewhat different from that of Fig. 1. In Fig. 5 a support 13* is shown 100 comprising an angle bar pivoted at 30 and connected at 31 for adjustment by slot 32, whereby the deckel wheel 10 carried at 33 may be adjusted.

It will be seen that the arrangement is 105 exceedingly simple and effective, and that complicated arrangements such as a pond and cooperating devices, are dispensed with. Also that the pressure in box 2 sends pulp along the wire.

It will be understood that changes and modifications may be made without departing from the spirit of the invention.

What I claim is:

- 5 1. The combination with the table and head box, of a spout or nozzle extending from the box to the table and arranged to discharge material upon the wire, means for controlling the flow of material from the box to the spout and means for controlling the flow of material from the spout to the wire.
- 10 2. The combination with the table and head box, of a spout or nozzle extending from the box to the table and arranged to discharge material upon the wire, means at the box for opening and closing the box end of said spout, and means at the discharge

end of said spout for controlling the size of the discharge orifice of said spout.

3. The combination with the head box or vat, of an outlet from the same to wire, means for adjusting the amount of flow from said outlet, and means for supporting deckel wheels from the head box.

4. The combination with the head box or vat, of outlet from the same to wire, means for adjusting the amount of flow from said outlet, and means for supporting deckel wheels from the head box, said supporting means being adapted to permit adjustment of said wheels.

In witness whereof, I hereunto subscribe my name this 2nd day of May, A. D., 1921.

ALONZO ALDRICH.
